(57) **CLAIM**

The ornamental design for an electrical connector, as shown and described.

DESCRIPTION

Cross reference is made to copending U.S. design patent application Ser. No. 29/866,442 entitled "Electrical Connection System" by Georg Wallensteiner, which was filed on even date herewith.

FIG. 1 is a perspective view of an electrical connector showing my new design;

FIG. 2 is a left side elevational view of the electrical connector of FIG. 1;

FIG. 3 is a right side elevational view of the electrical connector of FIG. 1;

FIG. 4 is a front side elevational view of the electrical connector of FIG. 1;

FIG. 5 is a rear side elevational view of the electrical connector of FIG. 1;

FIG. 6 is a top side plan view of the electrical connector of FIG. 1; and,

FIG. 7 is a bottom side plan view of the electrical connector of FIG. 1.

The dashed broken lines shown in the drawings illustrate portions of the electrical connector that form no part of the claimed design. The electrical connector is shown with a dash-dot-dash symbolic break in its length. The appearance of any portion of the electrical connector between the dash-dot-dash break lines forms no part of the claimed design.

1 Claim, 7 Drawing Sheets
